UNITED STATES PATENT OFFICE.

ROBERT GORTON, OF WEST NEWTON, MASSACHUSETTS.

HOSE-SUPPORTER.

1,086,290.

Specification of Letters Patent. Patented Feb. 3, 1914.

Original application filed November 8, 1911, Serial No. 659,174. Divided and this application filed February 14, 1913. Serial No. 748,820.

To all whom it may concern:

Be it known that I, ROBERT GORTON, a citizen of the United States, residing in West Newton, in the county of Middlesex and State of Massachusetts, have invented certain new and useful Improvements in Hose-Supporters, of which the following is a specification.

This invention relates to hose-supporters in which the stud member comprises a soft rubber button and a base plate of the type shown in Letters Patent of the United States No. 552,470, granted to me December 31, 1895, and the object of my present invention is to provide a new way of covering the base plate with a fabric or other non-metallic material and of holding the fabric in place on the base plate.

My invention is illustrated in the accompanying drawings, in which,

Figure 1 is a perspective view indicating how the rubber button is applied to the post of the base plate. Fig. 2 shows a vertical central section through the rubber button. Fig. 3 shows a transverse section thereof. Fig. 4 shows a vertical central section through the button illustrated in Figs. 2 and 3 and a base plate and post to which it is applied. Figs. 5 to 9 inclusive show how the base plate of the stud is covered with a suitable fabric. Fig. 5 is a perspective view of the stud with a covered base plate. Fig. 6 is a plan view of a piece of fabric applied to a base plate (shown in dotted lines) with the post which extends through the fabric and through the base plate shown in top plan. The parallel dotted lines in Fig. 6 indicate how the fabric is folded. Fig. 7 is a view similar to Fig. 6 with the fabric folded along the dotted lines shown in Fig. 6. The transverse dotted line in Fig. 7 shows how the fabric is next folded. Fig. 8 is a perspective view showing how the final fold is given to the fabric and how the post and button are disposed in the completed article. Fig. 9 is a view on an enlarged scale and in transverse section of the completed article.

In the several figures of the drawings, A indicates the rubber button, B the base plate, and C the central support or post. These three members constitute the stud of the hose-supporter and the patentable subject-matter of this stud *per se* is claimed in my application for Patent No. 659,174, filed

November 8, 1911, of which the application for this patent is a division.

The button A is made of soft rubber having the requisite clinging and yielding characteristics. It may be molded in any suitable way, given any appropriate shape and is provided with a flanged or enlarged head and a recess *a* extending from the bottom or outer end of the shank of the button into but not through the head thereof.

The base plate, which is of the usual shape and construction, has extending from it a post C having a head *c*. The post may be made by automatic machinery and secured by automatic machinery to the base plate.

The button shown is oblong and the recess *a* is correspondingly shaped, but other shapes may be given to the button and recess. The button is attached to the post by placing the former over the latter and then forcing the button over the post in the manner indicated in Fig. 1. When thus assembled the post forms a substantial support for the button and the latter will not be separated from the post by the strain to which it is subjected in use.

In order that no metal parts of the stud shall be exposed, I cover the base plate with suitable fabric or other non-metallic material in the manner shown in Figs. 5 to 9 inclusive. This is desirable in order that the stocking shall not be grasped or nipped between metallic surfaces and in order that no metal shall come into contact with the leg of the wearer. The plate may be covered by the webbing which ordinarily suspends the stud and this webbing may be folded over or around the base plate in various ways, or the plate may be covered by other material and suitably suspended or connected with other parts of the clasp. After the plate is thus covered the button may be pressed down over the post.

In Fig. 5 the base plate B is shown by dotted lines and is covered by a suitable fabric D. One piece of fabric is employed to cover both the inner and outer faces of the plate, being folded at *d* and stitched at *d'*. The post carried by the base plate extends through the fabric and the button A rests on the outer part of the fabric covering. I may, however, cover the base plate in the manner illustrated in Figs. 6 to 9 inclusive, where E indicates a piece of cloth or other

fabric applied to the base plate B, and C indicates the post carried by the base plate which extends through the fabric. The covering is first folded on the parallel dotted lines e 5 and will then assume the condition shown in Fig. 7, there being at this time a single thickness of fabric on the outer face of the plate and two thicknesses on the inner side thereof. Next the fabric is folded on the 10 line y of Fig. 7 and will assume the condition shown in Fig. 8, where, it will be observed, there is one thickness of fabric on the outer surface of the plate and five thicknesses on the inner side thereof. This is 15 more clearly indicated in Fig. 9. The fabric is then preferably stitched on the line d'. The stitching may, however, be differently disposed—it need not be located on the line d' but may be otherwise arranged 20 to connect the fabric above the button. By this construction the base plate is completely covered on its inner and outer faces, as well as at its edges, with a minimum of stitching, and a cushion is formed which, when 25 in use, will be interposed between the base plate and the leg of the wearer. It will be observed also that by the construction shown all parts of the base plate are permanently 30 inclosed and there is no danger of the side edges or other parts of the base plate being exposed by any shifting of the fabric. The post C may be attached to the base 35 plate either before the fabric is applied thereto or after it is applied and before it is folded, although the former procedure is preferable, the post being passed through a slit in the fabric. The button is applied to the post after the covering is completely 40 applied, or is in the condition shown in either Figs. 6, 7, or 8. In either case the button covers and holds down the edges of the slit in the fabric.

In the drawings I have shown as being 45 covered the ordinary slotted base plate. It is obvious, however, that the slots are functionless in the covered plate and an unslotted rectangular piece of metal may be used as the base plate if desired.

I claim as my invention,—

50 1. A stud, comprising a post-carrying base-plate, a slitted fabric folded around the base plate with the post extending through the slit, and a recessed elastic rubber button pressed over the post and down upon the fabric to thus cover and hold down the edges of the slit.

2. A stud, comprising a base plate, a button secured thereto and a covering for the base plate consisting of a fabric covering 60 the inner and outer faces of the base plate and permanently inclosing the side edges thereof and which is folded inwardly across the lower edge of the base plate and car-

ried upwardly across the back thereof to provide additional layers of fabric thereon. 65

3. A stud, comprising a base plate, a button secured thereto and a covering for the base plate consisting of a fabric folded over the base plate, stretched flat thereon close to and completely covering the outer face 70 thereof and further folded to cover the lower edge and to permanently inclose the side edges of the plate and continued upwardly from the said lower edge to cover the back of the base plate and to form additional fabric layers thereon. 75

4. A stud, comprising a base plate, a button secured thereto, and a covering for the base plate consisting of a fabric inclosing the inner and outer sides and the side edges 80 of the base plate said fabric being folded transversely across the under side of the base plate to provide additional fabric layers and form a cushion on said under side.

5. A stud, comprising a base plate, a button secured thereto and a covering for the base plate consisting of a fabric folded over the inner and outer sides of the base plate and also the side edges thereof and permanently inclosing them and stitched 90 near the upper end only of the base plate.

6. A stud, comprising a base plate, a button secured thereto, and a fabric covering for the base plate extending across the outer side thereof folded longitudinally on opposite sides of the base plate to form a plurality of thicknesses of material on the under side thereof and further folded transversely and passed across the bottom or under side of the base plate and stitched 100 above the upper end of the base plate.

7. A stud, comprising a post-carrying base plate, a slitted fabric through which the post extends and which is folded around the base plate to cover the inner and outer faces thereof and also its side and bottom edges, and a recessed elastic rubber button pressed over the post and down upon the fabric. 105

8. A stud, comprising a post-carrying 110 base plate, a slitted fabric through which the post extends and which is folded around the base plate to form a single thickness of material on the outer face thereof and to cover its edges and form a plurality of 115 thicknesses on its rear face, and a rubber button pressed over the post and down upon the fabric to thus cover and hold down the edges of the slit.

In testimony whereof, I have hereunto 120 subscribed my name.

ROBERT GORTON.
